UNITED STATES PATENT OFFICE.

FRANCIS M. PIPER, OF LYNN, MASSACHUSETTS, ASSIGNOR OF ONE-FOURTH
TO WILLIAM NORTON, OF SAME PLACE.

SUSPENDERS.

SPECIFICATION forming part of Letters Patent No. 352,348, dated November 9, 1886.

Application filed August 16, 1886. Serial No. 211,009. (No model.)

To all whom it may concern:

Be it known that I, FRANCIS M. PIPER, of Lynn, county of Essex, State of Massachusetts, have invented certain new and useful Improvements in Suspenders, of which the following is a specification, taken in connection with the drawings accompanying and forming a part hereof, in which—

Figure 1 is a view of a pair of suspenders, showing my improvement attached. Fig. 2 is a view of a modified form of my attachment.

The object of my invention is the production of suspenders which shall not only support the sides and back of the trousers, but shall also support the front thereof; and it consists in the construction and arrangement of a pair of straps extending from the front straps of the suspenders near the shoulder to the front of the waist of the trousers, as shown and hereinafter described.

My invention is simple, and will be readily understood from the following description, in which reference is had to the accompanying drawings.

25 A represents the shoulder-straps of a pair of suspenders. These I provide with buckles and eyes a, which may be set at any point on the straps A, as desired, thus allowing the straps B B to be raised or lowered. The straps B 30 are secured together at their lower ends, as shown, Fig. 1; and are there provided with a loop, C, having a button-hole by which it is secured to a button in the center of the waistband of the trousers. A button may be pro-

vided on the inside of the waistband for the purpose, although usually this is unnecessary, as the upper front button of the trousers will answer the purpose. The upper ends of the straps B are provided with snap-hooks b, or equivalent devices, by which the straps may 40 be readily secured to or released from the eyes a.

Instead of the buckle and eyes a and the hooks b, a spring hook of well-known construction may be used adapted to seize the 45 straps A at any point.

For some styles of waistcoat it may be desirable to separate the lower ends of the straps B, setting a piece between them and using two button-loops to button to the trouser-front, as 50 shown, Fig. 2. This arrangement will prevent the straps B B from showing when the waistcoat is low-cut.

Instead of the button-hole in the loop C, a metallic clasp or fastening of any well-known 55 construction may be used for attaching the loop to the trousers.

What I claim is—

The combination, with a pair of suspenders, of the straps B B and button attachment C, 60 secured between the shoulder-straps of the suspenders in front and buttoning to the front of the trousers, for the purposes and substantially as specified.

FRANCIS M. PIPER.
